UNITED STATES PATENT OFFICE

EDWARD SEYMOUR NICHOLAS, OF MONROE CENTER, ILLINOIS

MACHINE TO MAKE CONCRETE BUILDING BLOCKS

Application filed February 2, 1928. Serial No. 251,241.

This invention relates to a machine for making concrete building blocks. It provides a means to make the block shown and described in Letters Patent of the United States, No. 1,629,960 issued to me May 24, 1927 and is an improvement on the mold and core shown and described in Letters Patent of the United States No. 1,652,180 issued to me Dec. 13, 1927. This improvement aims to accomplish three purposes or objectives, each of which is desirable. First, it aims to provide a face down machine that will make these blocks rapidly; second, it provides a simple means to design the face of the blocks so they will appear well when laid in a wall; third, it provides a means of securing a closed joint between blocks in a wall with a minimum of labor and mortar. It is necessary to make the core in pieces to make this form of block face down. The face plate is designed so that a block will resemble brick and mortar in a wall. Grooves for mortar are made on the top, bottom and ends of a block; mortar is poured or forced into these grooves when the wall is building. Similar parts have the same number in each figure of the drawings.

Referring to the drawings:

30 Fig. 1 is a plan view of the machine.

Fig. 2 is a side elevation; the dotted lines show the outer side and ends of the mold box swung into unloading position.

Fig. 3 is a section taken on line 3—3 on 35 Fig. 2.

Fig. 4 is a section taken on line 4—4 on Fig. 2.

Fig. 5 is a section taken on line 5—5 on Fig. 1.

40 Fig. 6 is a plan view of an end plate for a common block.

Fig. 7 is a sectional view of an end plate used in making a corner block.

Fig. 8 is a face of a block designed to resemble brick and mortar in a wall.

Fig. 9 is a perspective view of a corner block designed to resemble brick and mortar in a wall.

50 Details of the machine are made plain by referring to the numbers in the drawings.

The main parts of the machine are a frame 11 on which is mounted a mold box having a core in it of irregular design that divides the block longitudinally. The mold box may be opened or closed between the ends 55 25 and back wall 33; the ends are hinged at 26 to the outer wall 46. The latch 17 on the frame engages lug 18 on each end to open or close the box. The latch opens by pressing down lever 16, which is hinged 60 to the frame at 70 and has a rod 32 connecting it with the latch. The spring 15 returns the latch to the closed position. When the latch is open, the outer wall 46, the face plate 14, and the two ends may be swung 65 outward on shaft 45 to the unloading position, shown by dotted lines in Fig. 2. The face plate is in the bottom when the mold box is closed and turns to perpendicular 70 position to unload. The back wall 33 is attached to the frame. A pallet 24 lays against the outer wall 46 when making a block. When the block is in unloading position the pallet is used to remove it.

The core divides the block longitudinally 75 into two parts. It forms lug 63 within the block at the middle, and lug 64 at the end as shown in Fig. 9. The common block has a lug 64 at each end. The middle lug is as wide as the lugs on both ends together. 80 These lugs extend inwardly from one side of a block toward the opposite side more than half of the distance between them. They overlap each other when laid in a wall. It is necessary to divide the core into sections to make this form of block in a face down machine. This core has five sections as follows: a piece at each end 27; two main cores 12 within the block; and a middle piece 85 37 between the main cores, or larger pieces. 90 The larger pieces of core 12 are parallel with each other, spaced apart and spaced above the bottom and below the top of the mold box. They may be moved with lever 19 95 which operates shaft 20; this moves lever 21 and pin 22 which engages and moves the cores 12. They may be pushed into or withdrawn from the mold box horizontally through holes in the back wall. A rod 13 100

attached at one end to each piece of core 12, guides it straight.

The middle piece of core 37 rests at each end on a lug 36. One lug is on the pallet 24 and the other on the back wall 33. This middle piece is not very thick; it lays between the larger pieces 12 on a level with their lower side. This piece 37 and the two larger pieces 12 form a cavity in which the middle lug 63 of a block is made. This piece is placed in position after the bottom of the box is filled with concrete and withdrawn from the block after it is turned to the unloading position.

15 The piece of core 27 attached to each end plate used to make a common block is shown in Figs. 1, 2, 3, 4, and 6. Fig. 1 shows it when the box is closed. Fig. 2 shows the back or outside of it. In Fig. 3 the dotted lines show it turned out of the mold box while filling the ends of the box with concrete up to that point; it is also shown in position when the block is in the box. Fig. 4 shows it swung outward with the end 20 plate. Fig. 6 shows it attached to the end plate.

This piece of core 27 is attached to a part 28 of an end plate 25 near the top and at right angle to it. This part of the end 28 is hinged at 30 near the top on the outside. A latch 29 on the outside holds it in position 30 while it is in the box and until it is removed from the block. This piece of core 27 is the same thickness as the middle piece 37. A 35 piece extends inward from each end plate to meet the top of the larger pieces of core 12, keeping the upper surfaces in line. This piece of core 27 has slots 31 cut on the inner edge through which iron tie rods 34 pass 40 to unite the parts of the block into a unit. Tie rods are used at each end of a common block; and at one end and a side of a corner block. Concrete is shown in the machine 45 in Figs. 3, 4, and 5.

45 The face of a block designed to resemble brick and mortar in a wall is shown in Fig. 8. A corner block with similar design is shown in Fig. 9. Each face has grooves 60 cut in it showing a design two bricks long and three bricks high with grooves resembling mortar joints. The design in Fig. 8, 50 has two full bricks at the top and bottom and one full brick and two half bricks in the middle row. The design in Fig. 9 has two full bricks in the middle row and a full 55 brick and two half bricks 62 in the top and bottom rows. Both designs are necessary to build a wall. One design is used to lay a course; the course next above it shifts the 60 block half its length in one direction and must have the other design to match it and make the proper effect. The half bricks are butted together in a course in a wall and a small amount of mortar forced into the 65 cracks to close them. The grooves 61 at the

end of a full brick and at the top and bottom of a block are half as wide as grooves 60 between the bricks. They show full size in a wall. The narrow grooves on the ends of a block are made by pads 48 on the plate shown in Fig. 6. An end plate used to make a common block designed as shown in Fig. 9 will have one pad in the middle row of bricks instead of two pads as in Fig. 6.

70 The face plate 14 produces blocks showing the faces in panels. It has slots 23 cut through it longitudinally and transversely. It is held together as a unit by webs on the back of it that bridge the slots. Movable steel bars 39 mounted in these slots, slide 75 inwardly and outwardly. The steel bars are fastened to a movable frame 38 which is mounted on the back of the face plate. The steel bars and movable frame are in contact with each other through openings between 80 the webs that span the slots. Shaft 40 is mounted on lugs 14' on the back of the face plate. Eccentrics 42 on each end of the shaft engage the movable frame 38. Trusses 44 extend outward from the back of the 85 face plate. Springs 43 are mounted between these trusses and the movable frame. They aid in moving the bars in the slots by keeping the proper tension on the movable parts. Lever 41 operates the shaft which 90 gives motion to the movable frame and bars. The steel bars are pushed into the mold box before it is filled with concrete. They produce the grooves 60 and 61 in the face of the 95 block and divide the face of the block into 100 panels. They are withdrawn from the block after it is tamped and before it is removed from the mold box.

An end plate 50 is shown in Fig. 7. It is used when making corner blocks having both 105 faces panelled as shown in Fig. 9. Slots are cut through this plate in the same manner and with a design corresponding to the slots in the face plate 14. Steel bars 52 are mounted to slide in these slots; they are attached to the movable frame 51 on the back of the end face plate. This end face plate, like the face plate 14, has the segments thereof held together by webs which bridge the slots. The movable frame 51 has a cam 110 projection 56 on the outside thereof. A stud 54 extends outwardly from the back of the end plate between the cams 56. Lever 55 is pivoted to this stud by cap screw 57 and it engages with the cams 56. Springs 53 are mounted between the back of the end plate and the movable frame. By turning the lever in one direction the steel bars are forced inward into the mold box when the end plate is in use. The springs force the 115 movable frame and steel bars outwardly when the lever is turned in the other direction. These bars are forced inward into the mold box before it is filled with concrete; they are withdrawn after the block is tamped 120 125 130

and before the end plate is moved away from the block.

5 Grooves 65 to receive mortar are provided on the top and bottom of the block running longitudinally near each side of it. Similar grooves are provided on the ends of a block running perpendicularly. The grooves on top and bottom are joined by grooves on the ends. Fig. 9 shows these grooves on a corner block. The grooves on the top and bottom of a block may be made by tongues 67 on the back wall and pallet; the grooves on the ends may be made by tongues 47 on the end plate. When blocks are laid in a wall 10 these grooves for mortar are matched with the grooves in adjacent blocks. Mortar is run or forced into the cavity to make a closed joint in the wall.

15 The process of making a block is as follows: Close the mold box with the end pieces of core swung outward; fill the bottom with concrete and move the main or larger pieces of core into the box; place iron tie rods in each end; fill the middle of the bottom and ends to the top of the larger pieces of core; place the middle piece of core in position and swing the piece of core on each end into the mold box and fill the box. Remove the larger pieces of core and open the box. 20 Turn the mold box to unloading position; remove the middle piece of core; turn each end outward from the block and remove the pallet with the block on it.

25 I claim:

30 1. In a concrete block machine, a mold box mounted on a frame, said box having means to open and close the same and a removable core within the box, the bottom of the box constituting a face plate, said face plate having slots cut through it in design, movable bars mounted in the slots, a movable frame on the back of the face plate having said bars moving therewith, and means to move the bars inward or withdraw them from the box.

35 2. In a concrete block machine, a mold box mounted on a frame, said box having means to open and close the same and a removable core within said box, the mold box 40 having a face plate that has slots cut through it in design, movable bars mounted therein, a movable frame on the back of the face plate, having said bars moving therewith, a shaft mounted on the back of the 45 face plate with one or more eccentrics that engage the movable frame, and a lever to operate the shaft and push the bars inward or withdraw them from the box.

50 3. In a concrete block machine, a mold box mounted on a frame, said box having means to open and close the same, and a removable core within said box the mold box 55 having a face plate that has slots cut through it in design, movable bars mounted in the slots, a movable frame on the back

of the face plate having said bars moving therewith, a shaft mounted on the back of the face plate with one or more eccentrics that engage the movable frame, a lever to operate the shaft, and springs to exert pressure between the movable frame and face plate to assist in moving the bars on withdrawing them from the box. 70

4. In a concrete block machine, a mold box mounted on a frame, said box having means to open and close the same, a removable core within said box, a part of said mold box being a face plate designed by slots cut through it, movable bars mounted in said slots, and means to move them inward and outward, in combination with an end plate for a corner block designed by slots cut through it, movable bars mounted in said slots, a movable frame on the back of the end plate having said bars moving therewith, a movable lever pinned to a stud on the back of the end plate, said lever being in engagement with a cam projecting from the movable frame whereby to move said frame one way by movement of said lever in one direction, and springs to exert pressure between the end plate and the movable frame tending to move the latter the other way. 75 80 85 90

5. In a concrete block machine, a mold box 95 mounted on a frame having a removable core within the same, and means to open and close the box, a part of said mold box being a face plate having movable bars mounted in slots cut through it in design, a movable frame on the back of the face plate, having said bars moving therewith, a shaft mounted on the back of the face plate, and having one or more eccentrics thereon engaging the movable frame, springs to exert pressure between the movable frame and face plate, and a lever to operate the shaft, in combination with an end plate having movable bars mounted in slots that are cut through it in design, a movable frame on the back of the 100 end plate, having said bars moving therewith, the movable frame having a cam thereon, a lever engaging the same, said lever being movably pinned to a stud on the end plate, and springs compressed between 105 the end plate and movable frame. 110 115

6. In a concrete block machine, a mold box mounted on a frame having a removable core within the same, and means to open and close the box, one part of the box being a face plate, the face plate being designed by steel bars mounted in slots cut through it in a design, a movable frame on the back of the face plate having said bars moving therewith, and means to move the bars inward or withdraw them from the box in combination with bars half as wide as the bars in the slots on each side of the face plate moving with the same movable frame 120 125 130 135

to make grooves of half size on the edges of a block.

7. In a concrete block machine, a mold box mounted on a frame, said box having means to open and close the same, and a core within said box that is made in parts and divides the concrete longitudinally, said core being composed of two rectangular block shaped pieces that are the same in size, parallel with each other, spaced apart and spaced above the bottom and below the top of the box, and a thin piece of core between the rectangular pieces on a level with their lower surface, and a thin piece of core attached to each end plate of the box, extending inwardly to meet the rectangular pieces on a level with their upper surface, the two rectangularly block-shaped pieces being insertable and removable horizontally while the box is closed and in loading position, and at least one of the other core pieces being removable perpendicularly after the box is opened.

8. In a concrete block machine, a mold box mounted on a frame, said box having means to open and close the same, and a core within said box that is made in parts and divides the concrete longitudinally, said core being composed of two rectangular block shaped pieces that are the same in size, parallel with each other, spaced apart and spaced above the bottom and below the top of the box, and a thin piece of core between the rectangular pieces on a level with their lower surface, and a thin piece of core attached to each end plate of the box, extending inwardly to meet the rectangular pieces on a level with their upper surface, there being lugs on opposed walls in said box for supporting at least one of the three thin core pieces, said pieces being adapted to be put into the mold box at different stages in the operation of making a block, and the one piece being arranged to be removed perpendicularly after the box is opened, the two rectangularly block-shaped pieces being movable into and out of the mold box horizontally while the box is closed and in loading position through openings provided 50 in one wall of the box.

In testimony whereof I have signed my name to this specification.

EDWARD SEYMOUR NICHOLAS.
